TRAIL BUILDER

Frank P. Lawler, Chicago, Ill., assignor to The Buckeye Traction Ditcher Company, Findlay, Ohio, a corporation of Ohio

Application November 28, 1940, Serial No. 367,521

2 Claims. (Cl. 37—144)

This invention relates to earth moving devices of the bulldozer or trailbuilder type which are adapted to be mounted on a tractor with the mold board or blade in advance thereof, the latter being usually disposed at a transverse angle to the line of advancing movement.

An object of the invention is to produce a device of the above character in which the mold board can be readily and conveniently adjusted about a horizontal axis by first loosening fastening devices and thereafter effecting the desired adjustment and without the necessity of bodily removing the mold board from its frame.

Another object is to produce a device of the above character in which the mold board is bodily separable from the supporting frame, thereby enabling the frame to be used in connection with the tractor as a bumper or pusher.

A further object is to produce an implement of the above character which can be positioned closely to the front end of the tractor to increase the efficiency of the machine and so mount the mold board that it can be angularly adjusted about a horizontal axis in an exceedingly simple and convenient manner.

A still further object is to produce a relatively simple and inexpensive implement of the above character which has the new and improved features of construction, arrangement and operation hereinafter described, and for purposes of illustration but not of limitation, an embodiment of the invention is shown in the accompanying drawings in which

Figure 1 is a top perspective view of a trailbuilder attachment secured to a tractor, the same being elevated to traveling position;

Figure 2 is a composite view showing in perspective the front end portion of the trailbuilder frame with the mold board separated therefrom;

Figure 3 is a front perspective view of a portion of the trailbuilder frame;

Figure 4 is a rear end elevation of the mold board on a somewhat reduced scale; and

Figure 5 is a longitudinal sectional view on the line 5—5 of Figure 4.

The illustrated embodiment of the invention comprises a tractor T to which is secured a trailbuilder attachment A. The trailbuilder attachment A comprises a mold board 10 which is disposed in upright position and has a downward and forward slanting blade surface 11. In spaced relation to the back of the blade surface 11 is a plate 12 which is suitably welded in position. Secured by welding centrally to the back of the blade surface 10 and passing through the plate 12 is a pin 13. The pin 13 projects a distance rearwardly of the mold board and provides a pivotal mounting therefore as will hereinafter appear. Formed in the back of the mold board are four arcuate elongate slots 14 which have an axis coinciding with that of the pin 13. In this instance it will be observed that two slots 14 spaced vertically from each other are arranged at opposite sides of the pin 13. Passing through the slots 14 are bolts 15 respectively, the heads being shaped to pass through the slots 14 and then be turned at right angles in order to prevent the bolts from coming loose from the slots. The bolts 15 have a loose sliding fit within the slots 14 so that the mold board 10 can move relatively to the bolts as will hereinafter appear.

Extending transversely of and in front of the tractor T is a cross beam 16 which is disposed relatively close to the forward end of the tractor 10 and is formed with a central opening 17 to receive the pin 13 on the rear face of the mold board. Fixed as by welding to the upper and lower sides of the cross beam 16 are blocks 18 which are apertured to receive the bolts 15 respectively. As indicated on Figure 1, nuts 19 engage the rear ends of the bolts 15 and, when tightened, draw the mold board 10 up tightly against the front face of the cross beam 16 and securely hold it in place.

When it is desired angularly to adjust the mold board 10 relative to the cross beam 16, the nuts 19 are loosened and the mold board can then be tilted about a horizontal axis. After the mold board has been rocked to the desired position, the nuts 19 are again tightened to hold the mold board in the adjusted position. Such adjustment can be readily and conveniently accomplished without detaching the mold board from its frame thereby materially facilitating the adjusting operation, it being merely necessary to lift the mold board from the ground so that it is free to be tilted.

Extending rearwardly from each end of the mold board 10 is a longitudinal beam 20 the forward end of which is connected to the cross beam for pivotal movements about a vertical axis, the front end of each beam 20 being forked to receive the adjacent end of the cross beam 16 therebetween. A bolt 21 passes through the end portions each of the beams 16 and 20 to enable the swinging movement to be accomplished. Each longitudinal beam 20 telescopes with a beam 22, the rear end of which is pivotally connected at 23 to the rear axle of the tractor T. The particular form of pivotal connection 23

is well-known to those skilled in this art and since it forms no part of the present invention, further description is not considered necessary. Carried by each beam 22 is a pair of bolts 24 which engage the adjacent beam 20 for locking the same in the position of longitudinal telescopic adjustment.

A pair of diagonal braces 25 extend from longitudinal beams 20 to the cross beam 16. A yoke is formed on each end of each of the braces 25 to fit over the beams 20 and 16 and a series of holes 26 in the cross beam 16 and holes 27 in the longitudinal beams 20 enable the cross beam to assume the desired angular position transversely of the track of movement. Obviously by loosening the braces, one or the other of the longitudinal beams 20 may be extended or retracted to effect the desired transverse angular adjustment whereupon the braces 25 are secured in the proper holes as will be readily apparent.

Fixed to the outer side of each of the braces 25 is a bracket 28 to which a sheave arrangement 29 is secured. A cable 30 is trained about the sheaves 29 and extend to the tractor T, eventually being connected to a power driven hoist H mounted at the rear end of the tractor. The hoist H is operated to raise or lower the trailbuilder attachment A which swings about its pivotal mounting with the rear axle of the tractor as is well understood in the art.

It will be manifest from the above description that this trailbuilder attachment is relatively simple in construction, easy to assemble and relatively inexpensive to manufacture. An outstandingly important feature resides in the detachability of the mold board from its frame so that the frame can be used as a bumper for any desired purpose. Another feature of importance is the adjustability of the blade by which it can be rocked about a horizontal axis to position the blade in the desired manner without in any way affecting the frame structure or removing the blade from the frame. This arrangement is also desirable since it can be positioned in close juxtaposition to the front end of the tractor which is always desirable in attachments of this character.

It is to be understood that numerous changes in details of construction, arrangement and operation may be effected without departing from the spirit of the invention especially as defined in the appended claims.

What I claim is:

1. Earth moving device for mounting on a tractor, comprising a cross beam arranged transversely and in close juxtaposition to the front of the tractor, longitudinally disposed beams connected to opposite ends of the cross beam and extending rearwardly along adjacent sides of the tractor, a mounting for the rear end of each of said longitudinal beams with the tractor, a pin loosely connecting an intermediate portion of the mold board on said cross beam enabling rocking movements of the former about a horizontal axis and enabling removal of the mold board from said cross beam, elongate arcuate slots having an axis common to said pin and arranged in said mold board, bolts having one end disposed in said arcuate slots respectively and adapted to extend through openings formed in said cross beam, and nuts engaging the ends of said bolts for rigidly securing the mold board in predetermined position against said cross beam, whereby removal of said nuts makes possible bodily separation of the mold board from the cross beam.

2. Earth moving device for mounting on a tractor, comprising a cross beam arranged transversely of and in close juxtaposition to the front of the tractor, longitudinally disposed telescopic beams pivoted respectively to opposite ends of the cross beam for movement about vertical axes, a pivotal mounting for the opposite ends of said telescopic beams respectively and the adjacent side of the tractor, diagonal braces connecting said telescopic longitudinal beams and said cross beam respectively adapted to be selectively secured in one of several positions for adjusting the position of the cross beam relative to the tractor, an upright mold board disposed in front of and in abutting relation to the front of said cross beam, a detachable pivotal mounting for connecting said mold board to said cross beam enabling angular adjustment of the mold board about a horizontal axis, elongate arcuate guides having an axis common to the pivotal mounting of said mold board and carried by said mold board, bolts passing through said slots and extending through openings in said cross beam, and nuts on said bolts for rigidly securing the mold board to said cross beam, thereby enabling angular adjustment of the mold board with respect to the cross beam without separation of the cross beam and mold board.

FRANK P. LAWLER.
